(57) CLAIM

The ornamental design for a plate for print head, as shown and described.

DESCRIPTION

FIG. 1 is a front view of a print head;

FIG. 2 is a top view thereof;

FIG. 3 is a right-side view thereof;

FIG. 4 is a left-side view thereof;

FIG. 5 is a rear view thereof;

FIG. 6 is a bottom plan view thereof;

FIG. 7 is a perspective view thereof; and,

FIG. 8 is an enlarged partial bottom view taken between lines 8—8 of FIG. 6.

The broken lines are for illustrative purposes only and form no part of the claimed design.
